UNITED STATES PATENT OFFICE.

WILLIAM LOEFFLER, OF SHEBOYGAN, WISCONSIN.

SANDING DRUM.

1,412,289.

Specification of Letters Patent. Patented Apr. 11, 1922.

Application filed February 28, 1919. Serial No. 279,848.

To all whom it may concern:

Be it known that I, WILLIAM LOEFFLER, a citizen of the United States, and resident of Sheboygan, in the county of Sheboygan and State of Wisconsin, have invented new and useful Improvements in Sanding Drums, of which the following is a description, reference being had to the accompanying drawings, which are a part of this specification.

10 The invention relates to sanding drums and has for its general objects to improve the construction of drums, and particularly to provide means for making a close joint between the opposite ends of the sand paper attached to the drum, to provide for quick removal and renewal of the sandpaper and to provide a simple and efficient means for balancing the drum.

20 The invention further consists in the novel construction and combination of parts hereinafter set forth and more particularly defined by claims at the conclusion hereof.

In the drawings:

Fig. 1 is a view of the device embodying 25 the invention, parts being broken away and parts being shown in section;

Fig. 2 is an end view of the device;

Fig. 3 is a section taken on the line 3—3 of Fig. 5;

30 Fig. 4 is an enlarged detail view of a portion of the drum shown in Fig. 3;

Fig. 5 is a vertical sectional view through the device;

Fig. 6 is a plan view of a modified form 35 of construction of drum;

Fig. 7 is a section taken on the line 7—7 of Fig. 5; and

Fig. 8 is a detail view taken on the line 8—8 of Fig. 7, parts being broken away.

40 The drum, designated generally by the numeral 7, is secured to a shaft 8 provided with a fixed pulley 9 and a loose pulley 10 for belt drive. The shaft 8 is journaled at its ends in bearing blocks 11, each of which has recesses 12 in its ends receiving packing 45 rings 13 which prevent dust from working into the bearing. Each bearing also carries a hood 14 secured thereto by a stud bolt 15 and a wing nut 16 and projecting inwardly 50 at the ends of the block and downwardly on the sides thereof to keep out dust. Each block 11 is pivotally supported upon a channel bracket 17 by bolts 17' so that the bearings are self-aligning. The brackets are 55 secured to the frame 18.

The drum 7 consists of a hollow metal cylinder 19 having a removable segment 20, a yielding backing 21, means for securing said backing to the outer face of the drum and means for removably securing a sheet of 60 sandpaper 21' or other abrasive material to the drum over the backing.

The drum 7 is provided with partitions 28 and ends 19' cast integral with the sides of the drum though it may be formed of sections. The segment 20 has depending portions 20' in line with the ends 19' and partitions 28. The drum is provided with a lengthwise extending opening 7' to receive the segment and with openings or notches 28' 70 in its ends and partitions in which the portions 20' of the segment are fitted and seated. The partitions are also provided with openings 34' extending from one side of the notches 28' therein to permit the clamping 75 plates 34 and 43 to pass said partitions.

The removable segment 20 is provided with a plurality of lugs 22 secured to or formed integral with the inner side of said segment and carrying adjustable set screws 80 23 provided with lock nuts 23'. The lugs 22 with the screws 23 act as fulcrums and fasteners so as to permit the segment being swung on one edge into or out of alined position with the shell of the drum. The segment 20 carries lugs 24 having alined holes 25 to receive a locking rod 26 which loosely passes through apertures 27 in the ends of the drum and in the partitions 28 within the drum and also passes through arcuate 85 slots 29 in arms 30 mounted on a shaft 31 journaled in said partitions and in the ends of the drum, said slots being eccentric to the shaft 31 so that the turning of said shaft 31 will cause the rod 26 to move inwardly and 90 thus pull inwardly on the lugs 24 and the segment so that it will be moved into a position contiguous with the remainder of the shell, as shown in Fig. 3. To assist in inserting the rod 26 one end has a threaded 100 bore receiving the threaded end of an extension shaft 26' provided with a handle.

In some instances, the segment 20 is held down contiguous to the surface of the drum by the rod 26 alone passed through the apertures 27 and 25.

The backing 21 of yielding material such as carpet or other fabric is secured at one end to the inner edge 32 of the drum and at the other to the inner edge 33 of the seg- 110

ment 20. In each instance it is secured by a clamping plate 34 extending the length of the interior of the drum and means for retaining said plate in clamping position, said plate being provided with pointed pins 36 which are forced through the carpet and are seated in openings 37 adjacent the edge to which the carpet is secured. To retain said plate in position a plurality of bolts 10 38, passed through the drum shell, apertures 39 in the plate and apertures 40 in washers 41, are provided with wing nuts 42 whereby the screwing up of the nuts 42 moves the washers 41 in engagement with the plate 34 15 to clamp it against the edge of the carpet engaging the inner periphery of the drum. The end edges of the sandpaper are secured to the edges 32 and 33 in each instance by a clamping plate 43 having apertures 44 in 20 line with washers 41 to permit movement of the plate 43 with respect thereto. The end edge of the sandpaper is clamped between the plates 34 and 43 by wing nuts 45 mounted on bolts 46 and bearing against the plate 25 43.

With this construction the backing may be held clamped while the sandpaper is readily removed by loosening up the nuts 45 to release the plate 43 from clamping engagement therewith so that said plate may be moved back upon the washers 41 and a new piece of sand paper then put in place and clamped to the drum and its segment by the plate 43 and nuts 45. When the edges 30 of the sandpaper are thus secured the segment 20 is swung down to the position shown in Fig. 3, as previously described, and in this way the backing and sandpaper are held tightly on the drum.

40 This manner of clamping the sandpaper to the drum and the segment to the drum by means within the drum, produces a tight joint with edges continuous with the drum surface and thereby prevents pounding at the edge of the joint and consequently prolongs the life of the sandpaper as it will wear on the complete circumference of the drum.

In order to balance the drum a plurality 50 of couplings 47 are adjustably mounted on the shaft and receive one of the ends of the threaded shafts 48 which at their other ends are screwed into apertures in the drum, after the coupling has been turned on the shaft 55 to the desired position so that a rough balancing adjustment may be made. These shafts 48 carry weights 49 adjustable thereon and secured thereto in adjusted position for fine balancing by set screws 50. The rods 60 and weights balance the clamping means previously referred to so that there is a complete absence of vibration while the drum is running, which is beneficial to the operator.

65 In the construction shown in Fig. 6, the adjoining edges of the drum and the removable

segment 20' similar to the segment 20 are formed at an angle to the axis of the drum which results in an even wearing of the sandpaper carried by the drum and, as shown in dotted lines, the clamping means 70 do not extend the length of the drum but separate clamping means similar to those previously described extend from each end to the intermediate portion of the drum.

Brackets 52 secured to the frame adjacent 75 one side of the drum and having curved supporting surfaces 53 are provided so that the segment 20 or 20' may be supported thereon during removal or replacement of the sandpaper.

80 What I claim as new and desire to secure by Letters Patent is:

1. In a sanding drum, the combination, 85 with a shaft, of a hollow drum mounted thereon and provided with a movable section, projections on said section engaging the inner side of the drum adjacent one joint between said section and drum, a piece of abrasive material removably secured at the other joint between said section and drum, 90 lugs extending inwardly from said section, a revoluble locking shaft mounted within the drum, arms mounted on said shaft and provided with eccentric slots, and a shaft passing through said slots and apertures in 95 said lugs whereby said segment will be moved inwardly to a position flush with the drum and retained in this position on turning said locking shaft.

2. In a sanding drum, the combination 100 of a hollow drum having solid ends and a partition and provided with a lengthwise extending opening in its side and notches in said ends and partition, a segment fitting into said opening and having portions seated in said notches, and means including 105 clamping plates for securing a piece of abrasive material to said segment and drum, said partition having a notch therein extending from one side of the first named notch 110 through which said clamping plates pass.

3. In a sanding drum, the combination, 115 with the drum, of a clamping flat bar, clamping bolts carried by the drum for securing backing material between said drum and said bar, a second clamping flat bar having openings through which said clamping bolts pass, nuts for said bolts, and other clamping bolts carried by the first bar for securing a piece of abrasive material between said 120 bars.

4. In a sanding drum, the combination, 125 with a shaft, of a hollow drum mounted thereon and provided with a removable section, fulcruming projections on said section engaging the inner side of the drum adjacent one joint between said section and drum, a piece of abrasive material surrounding the drum, clamping plates on the section and drum receiving the edges of said 130

abrasive material within the drum at the other joint between said section and drum, and means within the drum for moving the section to bring its surface contiguous to 5 the surface of the remainder of the drum.

5. In a sanding drum, the combination with the drum, of a clamping flat bar, clamping bolts carried by the drum and passing through openings in said bar, spac- 10 ing washers on said bolts engaging said bar, wing nuts on said bolts for clamping the bar to secure backing material between said drum and said bar, a second clamping flat bar having openings through which said 15 bolts and washers pass, clamping bolts car-

ried by the first bar and extending through openings in the second bar, wing nuts mounted on said last named bolts for bringing the bars together to secure a piece of abrasive material between them, said washers permitting relative movement between the bars to permit replacement of abrasive material between them without loosening the second bar. 20

In testimony whereof, I affix my signa- 25
ture, in presence of two witnesses.

WILLIAM LOEFFLER.
